VALVE LIFTER

Samuel M. Jones and Lawrence P. Reichard,
Youngstown, Ohio; said Jones assignor to said
Reichard

Application April 25, 1945, Serial No. 590,252

2 Claims. (Cl. 29—218)

1

This invention relates to a valve lifter and more particularly to a valve lifting tool adapted for use in connection with Cadillac and LaSalle V-8 motors.

The principle object of the invention is the provision of a valve lifter tool formed to facilitate the removal or replacing of keys on the valve stems of a motor.

A further object of the invention is the provision of a valve lifting tool particularly adapted for use with a Cadillac or LaSalle V-8 motor to facilitate the installation of valves therein, and particularly the installation of keys on the said valves which normally retain the same in tensioned position.

A still further object of the invention is the provision of a valve lifter tool having means for catching and retaining keys accidentally dropped during an inserting operation.

The valve lifting tool shown and described herein has been designed to make possible the rapid installation of valves in a Cadillac or LaSalle V-type engine and particularly to facilitate the installation of the keys upon the keyways of the various valve stems of the engine prior to their being held by the key seats of the valve assemblies. It is well known that intake and exhaust manifold valves are employed in internal combustion engines to control the orifices establishing communication between the inlet and exhaust manifolds and the cylinders and cylinder head assemblies. It is also well known that such valves each consist of a single valve having a depending valve stem which is in turn provided with a pair of keyways near its lowermost end. These keyways serve as a means of establishing a bearing surface for the lowermost portion of the valve tensioning spring which is positioned about the valve stem and which engages a key seat also positioned about the valve stem and which engages keys positioned on the valve stem on the said keyways. In a Cadillac or LaSalle V-type engine, hydraulic valve lifters are employed, which valve lifters are part of the engine assembly and which directly engage the cam shafts of the engines and transmit the movement of the cams thereon to the bottom of the plurality of intake and exhaust valves. It is also known that upon the removal of such hydraulic valve lifters the possibility of dropping the keys from the valve stems when removed is very great and as they will drop directly into the crank case of the engine they constitute a serious hazard. The present invention has been designed to insure against such accidental drop.

2

ping of the keys and further to facilitate their removal and reinstallation as is necessary at such times as the valves are to be ground or replaced in rebuilding or overhauling of the engine.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

15 The invention is illustrated in the accompanying drawing wherein—

Figure 1 is a side elevation of the valve lifting tool in operative location with respect to a valve spring and key seat and the cam shaft of a V-type internal combustion engine.

Figure 2 is a top plan view with parts in cross section taken on line 2—2 of Figure 1.

Figure 3 is a top plan detailed elevation taken on line 3—3 of Figure 1.

25 By referring to the drawings and Figure 1 in particular, it will be observed that the valve lifting tool consists of a pair of arms 10 and 11 which are pivoted to one another by means of a pivot 12. The arm 11 is provided with an upwardly turned end 13 having an axially extending opening formed therein and is adapted to slidably receive a shaft 15, one end of which is pivoted as by means of a pivot 16 to an uppermost section 17 of the upper arm 10 and the other 30 end of which is threaded, as indicated by the numeral 18, and adapted to threadably engage a threaded opening in a rotatable handle 19. A washer 20 is positioned between the handle 19 and the bearing surface of the end 13 of the lower arm 11, adjacent the opening 14, so that when the handle 19 is revolved clockwise on the threaded shaft 18, the shaft is drawn outwardly through the opening 14 so as to move the upper arm 10 and cause an extension 10A thereof to 35 move away from the lower arm 11. A coil spring 21 is positioned about the shaft 18 between the upper arm 10 and the end 13 of the lower arm 11, and the spring 21 is normally compressed at such time as the handle 19 is revolved clockwise drawing the shaft 18 outwardly therethrough. The spring 21 serves to return the upper arm 10 to position against the lower arm 11 at such 40 time as the handle 19 is revolved in a counter-clockwise direction.

45 Still referring to Figure 1, it will be seen that

the extension 10A of the upper arm 10 is provided with a pivotally affixed, semi-cylindrically formed member 22 and includes a base 23 and a top 24, the top 24 having a centrally located opening 25 therein and an annular shoulder 26 thereabout. As illustrated in Figure 1, the semi-cylindrical member 22 is mounted upon the extension 10A of the upper arm 10 by means of a screw 27 positioned in an opening in the extension 10A of the upper arm 10 and engages a threaded opening in the base 23 of the semi-cylindrical member. In Figure 1 a valve stem is indicated by the numeral 28 and a valve spring by the numeral 29. A key seat 30 is shown positioned immediately beneath the lowermost portion of the valve spring 29 and it will be observed that it is flanged around its periphery to cause it to retain the valve spring 29 in appropriate position thereon. The key seat 30 is also provided with a depending, semi-cone shaped flange 31 which is adapted to engage a pair of oppositely disposed keys 32 and 33 which are formed to register with keyways 34 formed in the valve stem 28 near its lowermost end. As illustrated in Figure 1, the lower arm 11 is shown positioned on a cam shaft 35 and it is obvious that it may be positioned on any other appropriate structure to establish a suitable purchase for the tool. In Figure 1 the operation of removing or replacing the keys 32 and 33 has been partially completed, it being observed that after the removal of the hydraulic valve lifters, which are normally interposed between the lowermost end of the valve stem 28 and the cam shaft 35, the valve lifting tool with its arms 10 and 11 is positioned between the cam shaft and the key seat 30 on the valve stem 28. In such position, the lower portion 31 of the key seat 30 depends into the semi-cylindrical member 22 of the lifter and the keys 32 and 33 are completely within the semi-cylindrical member. In such position, the handle 19 is revolved upon the threaded shaft 18 to cause the extension 10A of the upper arm 10 to be moved away from the lower arm 11 (upwardly) thereby lifting the key seat 30 and its key engaging, depending flange 31 away from the keys 32 and 33 and thereby permitting the same to be removed. In the event that the keys 32 and 33 fall from their position on the keyways 34 of the valve stem 28, they will be caught by the semi-cylindrical member 22, and when this occurs the valve lifter tool's operation is reversed so as to retract the arms 10 and 11 of the tool and thereby permit the valve spring 29 and the valve itself to be removed.

By referring now to Figure 3 of the drawings, it will be observed that the semi-cylindrical member 22 is formed with an open side which is partially turned with respect to the longitudinal axis of the device, and which open side permits access to the interior of the semi-cylindrical member 22 and thereby facilitates the removal of the keys therefrom or the installation of keys 32 and 33 upon a valve stem 28 positioned therein as indicated in Figure 3. It will be observed that ample room is provided for the manual positioning or removal of the keys 32 and 33, or an automatic tool commonly employed for installing keys on the keyways of a valve stem may be used, as desired.

In installing valves in an engine, the valve lifter tool is particularly advantageously employed in that it cuts down the time required from several hours to a relatively few minutes. In such an installation operation, the tool is po-

sitioned with the lower arm 11 on the cam shaft or other suitable purchase, and the semi-cylindrical member is positioned in engagement with the key seat 30 beneath the spring 29 of the valve stem 28 and the tool then manipulated to cause the upper arm 10 and particularly its extension 10A to move upwardly with respect to the lower arm 11, which action compresses the valve spring 29 and makes available the completely exposed, lowermost end of the valve stem 28 which has the keyways 34 formed therein. In such exposed and, therefore, readily accessible location and in protected relation by reason of the semi-cylindrical member 22, the keys 32 and 33 may be readily installed on the keyways and upon such installation the handle 19 may be manipulated slightly to permit the device to retract partially thereby bringing the depending flange 31 of the key seat 30 into operative engagement with the keys 32 and 33 and thereby hold the same on the valve stem 28 and in appropriate position on the keyways 34 thereof. Thus, in a single, simple operation the installation of the valve keys is accomplished. In the event that the keys are dropped or that they do not register correctly with the keyways and drop by reason of misalignment, they are caught by the semi-cylindrical member 22 and do not drop into the exposed crank case of the engine. When this occurs, the tool may be retracted sufficiently to permit the same to be withdrawn from the motor and the keys recovered and reused or another set of keys may be installed and the keys left in the bottom of the semi-cylindrical member until such time as the operation is completed on the particular valve.

By referring to Figure 2 of the drawings, it will be observed that the extension 10A of the upper arm 10 is formed on the upper arm 10 or attached thereto by means of extensions 10B of the arm 10 engaging a slot 10C in the extension 10A and being turned outwardly and, in effect, riveted to secure the extension 10A to the upper arm 10 of the tool. In Figure 2, the cross sectional elevation of the semi-cylindrical member 22 is shown, it being observed that the cross section is taken through the annular shoulder 26 thereof and that the cross sectional view also illustrates the key seat 30 and the upper ends of the keys 32 and 33 as well as the valve stem 28.

It will thus be seen that a simple and efficient valve lifter tool has been disclosed which incorporates as its principle point of novelty the semi-cylindrical member 22 which makes possible the rapid and efficient removal and/or installation of valves in a Cadillac or LaSalle V-type motor without the heretofore danger of misplaced keys dropping into the crank case of the engine and the necessity of subsequently removing the same. It will also be seen that the device forms an efficient means of compressing the valve spring with respect to the valve stem and thereby permits the rapid installation of the keys upon the valve stem. The device is of relatively simple and sturdy construction and is very effective in its indicated use.

Having thus described our invention, what we claim is:

1. In a valve lifting tool having a pair of arms pivoted to one another and screw means engaging the same for moving the arms with respect to one another, a semi-cylindrical body member having an unbroken base mounted on one of the said arms and at right angles thereto, said semi-cylindrical body member having an annular

shoulder located inwardly from the uppermost end thereof, a side section of the semi-cylindrical body member being cut away below the said annular shoulder to permit access to the interior thereof, the uppermost end of the said semi-cylindrical member adapted to be engaged on the lower end of a valve spring so that it will compress the same when it is moved upwardly thereagainst by the said arms and screw means.

2. In a valve lifting tool having a pair of arms pivoted to one another and having screw means engaging the same for moving the arms with respect to one another, a semi-cylindrical body mounted on the outermost end of one of the said arms and at right angles thereto, said semi-cylindrical body member having an annular shoulder formed therein inwardly from its outermost end and having a side section cut away beneath the said annular shoulder to permit access to the interior of the semi-cylindrical body member, an unbroken bottom section formed integrally with said semi-cylindrical body member, the said semi-cylindrical body member adapted to be en-

gaged beneath the bottom of the valve spring so that it will compress the same when it is moved upwardly thereagainst by the said arms and screw means, the semi-cylindrical body member being mounted on the said arm in an adjustable manner.
